UNITED STATES PATENT OFFICE.

ALFRED E. MOON, OF AKRON, OHIO, ASSIGNOR TO THE B. F. GOODRICH COMPANY, OF NEW YORK, N. Y., A CORPORATION OF NEW YORK.

CORNER BUMPER.

Application filed November 24, 1920. Serial No. 426,327.

To all whom it may concern:

Be it known that I, ALFRED E. MOON, a citizen of the United States, residing at Akron, in the county of Summit and State of Ohio, have invented a certain new and useful Corner Bumper, of which the following is a specification.

This invention relates to bumpers for preventing damage to walls and household articles in the movement of the latter about a room, and is particularly applicable to carpet sweepers, floor polishers and such contrivances intended to be moved rapidly over a floor and to pass close to baseboards, table legs, etc. It has been common to use corner bumpers for such articles and to secure the same in place by means of a cord passing around the article and threaded through a tubular bumper at each corner, but such bumpers in manufacture have been given a permanent elbow form, the hole which runs lengthwise therethrough making a turn of approximately 90°. Such permanent curve of the longitudinal aperture makes the manufacture of such bumpers difficult and expensive, a separate mold cavity and mandrel being required for each bumper, and the sharply-curved mandrel being difficult to remove.

The main objects of my invention are to provide a corner bumper which can be more easily applied, will occupy less packing space in shipment and storage, and can be more rapidly and economically made.

Of the accompanying drawings:

Fig. 1 is a perspective view of a carpet sweeper provided with a set of my improved corner bumpers.

Fig. 2 is a perspective view of one of the bumpers in its natural or unbent condition.

Fig. 3 is a plan view of the same.

Fig. 4 is a perspective view of a blank piece of rubber stock adapted to be placed in a mold to form a plurality of the bumpers.

Fig. 5 is a perspective view of the bottom section of a mold with an unsevered series of the bumpers therein and a mandrel in molding position.

Referring to the drawings:

10 is a rubber stock blank of straight tubular form having a cylindrical, longitudinal hole therethrough, its wall being thickened at diametrically opposite parts 11, 12, the exterior, cross-sectional form being somewhat elliptical. I prefer to form such

blanks by the use of a tubing machine, cutting the tube to proper lengths such as that shown in Fig. 4.

13 is the bottom section of a mold adapted to carry out my invention, said mold being formed with a molding cavity, occupied by an unsevered string or series of bumpers 14 in Fig. 5; with bearing surfaces 15 on each side of said molding cavity, of which only one is visible in Fig. 5; and with large overflow cavities 16, 16^a outside of said bearing surfaces, 17 is a mandrel fitted into end notches 18 in the mold section 13, which are adapted to hold it preferably in approximately a central position in the molding cavity. 19, 19, are dowel pins at the corners of the mold section adapted to register the top mold section when placed thereon, and 20 is an opening lug on the mold section.

In the molding operation, the blank 10, being suitably formed as stated, is mounted upon the mandrel 17 and placed in the mold cavity with the protruding ends of the mandrel in the notches 18 of the mold section 13 and with one of its thickened walls 11, 12 adjacent the bottom of the mold cavity. The top mold section is then placed in position thereon and the usual molding and vulcanizing operation is performed. The overflow cavities 16, 16^a are made large in order that blanks having a considerable excess of stock may be used, the blanks thus not requiring to be weighed to size.

When the cure is completed the series of bumpers is removed from the mold and from the mandrel and thereafter cut apart crosswise at the points indicated by 21, 21, in Fig. 5, into a plurality of individual bumpers such as that shown in Fig. 2. However, I do not limit myself to the molding of an undivided string of the bumpers.

The form of mold is such that each bumper has the general form of a short tube with a circular, longitudinal aperture 30; a longitudinally and laterally rounded exterior face 22; parallel flat exterior faces 23, 23 adjacent thereto; flat exterior faces 24, 24 opposite the aforementioned rounded face 22, at the end regions of the tube, said faces 24, 24 slightly diverging from the longitudinal aperture 30 toward the ends of the tube as shown clearly in Fig. 3. The wall between the longitudinal aperture 30 and each of the attachment faces 24 is thus of increasing thickness toward the ends of the bumper, so

that the pull of the retaining cord will have a strong component in such direction as to hold the ends of the bumper firmly against the sweeper, or such other object as it may be attached to. 25, 25 are wedge-shaped notches extending laterally part way across the bumper from its flat side, forming a semi-articulated structure with a middle and two end sections A, B, B. Each of these notches has approximately equal sides and an angle of nearly 45°. They cut into and extend about half way across the longitudinal aperture 30, toward the curved face 22. Between said notches, and opposite to the curved face, the wall of the tube is relatively thick and is externally formed with a central longitudinal lug 26 having a plane face parallel with the longitudinal aperture 30 and flanked by segment-shaped recesses having concave arcuate walls 27, 27.

In placing the bumpers in position on the carpet sweeper they are bent to a curved form fitting the corners of the sweeper, the bending being facilitated by the presence of the wedge-shaped notches 25, 25, the converging faces of each notch substantially abutting each other when the bumper has been bent to position, as shown at 28, 28 of Fig. 1.

30 The bumpers are secured in place upon the sweeper by the cord 29 encircling the carpet sweeper and threaded through the longitudinal aperture or channel 30 of each bumper, the resiliency of the lug 26, embracing the corners of the sweeper, assisting to keep the cord 29 taut.

Owing to the fact that the bumper in its natural condition is substantially straight, as shown in Fig. 3, it is easily strung on the cord and may also be packed in quantities with very little waste space.

The longitudinal channel obviously may

be formed, by a suitable mandrel, either circular, as shown, or of other closed or open cross-sectional form, but I prefer a closed 45 circular form, as it centers the cord with relation to the walls 24 and the lug 26, and the outer side fully covers the cord 29.

Various modifications may be made. For example I do not wholly limit myself to 50 using a perfectly straight mandrel. Also, while I prefer to form the bumper with the end faces 25, 25^a of the middle section A parallel and at right angles to the longitudinal aperture 30, this may be varied. 55

I claim:

1. A longitudinally channeled rubber bumper having two substantially V-shaped recesses extending part way across the bumper and into its channel and dividing its 60 inner half into a middle section and two end sections adapted to assume a closed form when the bumper is bent around a corner.

2. A rubber bumper formed with a channel adapted to seat a retaining cord, said 65 bumper being adapted to fit around a corner of its mounting, and the wall between its attachment face and its channel increasing in thickness from its middle toward its ends.

3. A rubber bumper formed with a longitudinal aperture therethrough, a longitudinally, and laterally rounded outer face, attachment faces opposite to said rounded face and diverging from said aperture towards the ends of said bumper. two wedge-shaped 75 notches between said attachment faces, said notches extending substantially half way across said longitudinal aperture and having their adjacent sides at right angles thereto, and a lug between said notches. 80

In witness whereof I have hereunto set my hand this 18th day of November, 1920.

ALFRED E. MOON.
